August Schaffer Inventor

By Lincoln Finch his Attorney

UNITED STATES PATENT OFFICE.

AUGUST SCHAFER, OF COLUMBUS, OHIO.

STOVE.

1,380,842.

Specification of Letters Patent. Patented June 7, 1921.

Application filed May 26, 1919. Serial No. 299,719.

To all whom it may concern:

Be it known that I, AUGUST SCHAFER, a citizen of the United States, residing at Columbus, in the county of Franklin and State of Ohio, have invented a certain new and useful Improvement in Stoves, of which the following is a specification.

Gas heating stoves as at present in common use are enormously wasteful of heat. 10 The object of the present invention is to provide means for conserving and utilizing much of such heat and the invention consists in a modification of such stoves and the provision of means whereby a large part 15 of the heat is stored and the necessity for the continuous consumption of fuel avoided.

The invention is embodied in the example herein shown and described, the features of novelty being finally claimed.

20 In the accompanying drawing—

Figure 1 is a vertical sectional view on the line I—I Fig. 2.

Fig. 2 is a top plan view with a part broken out.

25 Fig. 3 is a horizontal section on the line III—III Fig. 1.

Fig. 4 is a detail section of the burner on a larger scale.

In the views 5 designates the body of the 30 stove which is generally of sheet metal and has its fire plate 6 inclined with its upper portion nearer the front so that its rear side shall form a seat for a removable slab 7 of soap stone, fire clay or other refractory heat 35 absorbing material. Said slab is substantially coextensive in facial area with the back of the fire plate. Hinged at 8 is a hood 9 fitting upon and covering the upper end of said body portion. Within the said hood 40 are small brackets 10 forming a seat to receive a removable slab 11 of material like that used to form the slab 7; and said slab is of a size to fit rather closely within the boundaries of the hood. The brackets 10 are 45 so located that the slab 11 lies in such spaced relation to the upper end of the fire plate and slab 7 as to provide room for the passage of the flame and products of combustion between the slabs and against the 50 under side of the slab 11 so as to thoroughly heat the same. The cross plate 9^a at the top of the front of the stove serves to direct the flow of such products to such passage. The hood has hinged to its upper end 55 a cover 12 so that the slab 11 may be removed or a cooking vessel 13 or other ob-

ject to be heated placed upon the slab. The cover is provided with a latch at 12^a. 14 designates the outlet for the products of combustion. This is placed low on the back 60 of the stove so that the products of combustion shall be caused to flow downward across the back of the slab 7 as indicated by the arrows. Said outlet 14 contains a damper 14^a to shut off the escape of heat 65 up the chimney when the fire is extinguished. The slab 7 receives heat from both sides. If, after the fire is extinguished, it is desired to permit the heat from the slabs to come abundantly into the room the 70 hood with the slab 11 is turned backward to rest on a bracket 15 as indicated by broken lines Fig. 1.

The slabs 7 and 11 are each provided with a hole as seen at 7^a and 11^a respectively to receive an instrument, as for example the end of an ordinary stove poker—for the purpose of lifting them from the stove. The occasion for such removal would be in a mild season as when the weather becomes suddenly warm and much heat is not desirable. The ordinary gas burner includes in the present instance the gas supply pipe 16 placed as usual to discharge gas through burner holes 17 in the upper wall of the 80 bottom chamber of the stove along and near the lower edge of the fire plate 7.

When the slabs are of suitable size they absorb large quantities of heat and give it off gradually. Therefore upon retiring at 90 night the fire may be extinguished with the assurance that the room will be kept comfortable until the morning.

The forms of the parts can be changed without departing from the gist of the invention as claimed.

What I claim is:

1. A stove including in combination, a body having a burner, a fire plate the back of which forms an upright seat for a slab, 100 a removable slab on said seat, a hood having a seat for a slab, a slab of heat absorbing material on that seat, said seat being in spaced relation to the upper end of the first mentioned seat, said body provided with a vent in its rear below the upper end of the first mentioned seat whereby the products of combustion are deflected by the second mentioned slab across the back of the first mentioned slab.

2. A stove including in combination, a body having a burner, a fire plate the back

of which forms an upright seat for a slab, a removable slab, heat absorbing material on said seat, a hood having a seat for a removable slab, said seat being in spaced relation to the upper end of the first mentioned seat, a slab of heat absorbing material on said seat, said body provided with a vent in its rear below the upper end of the first mentioned seat whereby the products of combustion are deflected by the second mentioned slab across the back of the first mentioned slab, and a removable cover for said hood.

3. A stove including, in combination, a body having a burner, a fire plate the back 15 of which forms an upright inclined seat for a slab, a removable solid slab of heat absorbing material on said seat, a removable closing hood for the stove in spaced relation to said seat, said body provided 20 with a vent in its rear opposite the lower end of said slab whereby the products of combustion are passed across the back of said slab.

AUGUST SCHAFER.
